EYELASH CURLER

Charles M. Palmer, Washington, D. C.

Application May 10, 1944, Serial No. 534,845

28 Claims. (Cl. 132—32)

1

This invention is concerned with a functionally and structurally improved eyelash curler for advantageously enhancing the appearance of human eyelashes. Most eyelash curlers of the prior art utilize a resilient or rubber pad generally carried by a slideable jaw and the eyelashes to be crimped are initially interposed between a fixed jaw of the curler and the resilient pad which is moved against the fixed jaw to crimp the eyelashes. In some instances, prior to the insertion of the eyelashes into the curler, adjuncts, such as, certain salves, creams or lubricants are utilized to treat or initially process these lashes. These adjuncts have the tendency to adhesively unite the pad to the lower slideable jaw. These adjuncts also have the tendency to harden the resilient pad, thus destroying its effectiveness. Also due to aging the resilient pad in some instances becomes brittle. Because of such processing of the resilient pad, occasionally it is necessary to replace it by a relatively new pad. To this end, where the old pad has become undesirably processed by lubricating adjuncts or hardened due to aging at times it is quite a difficult task to effectively remove it apart from digging it out of its supporting jaw. Often this operation is tedious and a special tool is needed. In certain instances convenient access to all parts of the processed pad could not be readily had. In other instances where a substituted pad was desired the user relied upon the source of sale or manufacture to make the desired substitution and of course under needless expense. The chief object of the invention is to provide serviceable means in an eyelash curler to permit convenient access to the interior of the pad supporting jaw for readily positioning or withdrawing the pad therefrom. The invention has as another object the provision of bodily and movably guided disconnectable components or complements comprising pad supporting means movable relatively towards and away from a fixed jaw of the eyelash curler. A further object is realized in the provision of complementary components defining a channeled member adapted to be opened or closed in the movement of one of the components away from or towards its companion component. The invention comprehends as a further and important object the provision of a novel resilient pad supporting member in an eyelash curler wherein the supporting member is slidably guided relative to a fixed jaw and wherein a door of the supporting member is swingable to allow convenient insertion of the rubber pad in the supporting member or

2

removal therefrom and wherein novel movably guided latch means is employed for desirably disconnectably locking the swingable door to sustain the pad in a slightly clamped position. Other important objects, features, and advantages will appear from the following detailed specification considered in the light of the accompanying drawing wherein:

Fig. 1 is a perspective view of the eyelash curler, illustrating in full lines the separable complementary pad holding components closed and showing in dash lines one of the components or closures swung outwardly to allow convenient access to the resilient pad.

Fig. 2 is a front view of Fig. 1 however showing the lower portions of the handles cut off and the slideable jaw in a clamping position against the fixed bar or jaw.

Fig. 3 is a fragmentary front view of the curler illustrating the door unlocked and swung laterally to provide full access to the rubber or resilient pad.

Fig. 4 is a view similar to Fig. 3 but with the rubber pad removed or withdrawn from the slideable jaw.

Fig. 5 is an enlarged view of Fig. 1 showing the rotatably guided latch interlocked with the swingable door of the slideably guided jaw.

Fig. 6 is an enlarged sectional view on the line 6—6 of Fig. 5 illustrating the latch interlocked to hold the swingable door closed.

Fig. 7 is a view similar to Fig. 6 however illustrating the door unlatched.

Fig. 8 is a perspective view of the slideable jaw illustrating the complementary components thereof fully separated or open.

Fig. 9 is a vertical sectional view on the line 9—9 of Fig. 2 however showing the lower slideable jaw spaced from the upper fixed jaw for permitting insertion of the lashes to be curled or crimped between the jaws.

Fig. 10 is a view similar to Fig. 9 depicting the slideable jaw in a raised position preparatory to crimping of the eyelashes interposed between the jaws.

Fig. 11 is a view similar to Fig. 10 showing the slideable jaw at its completely raised relation at which time the eyelashes between the jaws have been crimped.

Fig. 12 is a fragmentary front view of a reinforced link adapted to be fixedly secured to one of the components of the pad support and adapted to be rotatably associated with the pivoted handle of the curler.

Fig. 13 is a bottom view of the link illustrating

the ends thereof offset for purposes of facilitating assembly with the pivoted handle.

Fig. 14 is a fragmentary view of one upper corner of the link.

Fig. 15 is a fragmentary view of the slidably guided jaw.

Fig. 16 is a detail view showing the link secured to the slidably guided jaw.

Fig. 17 is an enlarged perspective view showing the rotatable latch interlocked with the swingable door.

Fig. 18 is an enlarged perspective view of the latch, and

Fig. 19 is a front elevational view of the rubber pad.

The curler is characterized by a frame F of suitable wire defining upstanding sides or tracks 10 and 11 integral with the downwardly converging portions 12 merged with spaced flattened portions 13 integral with juxtapositioned extensions 14 merging into loop 15. By this arrangement the lower part of the frame characterizes a handle or manipulating portion.

Pivotedly interposed between the spaced flattened portions 13 is a crank or offset portion generally denoted 16 which comprises juxtapositioned parts 17 of the juxtapositioned extensions 18 which terminate into the loop 19. The juxtapositioned flattened portions 17 of the crank 16 are pivotedly mounted on a fulcrum pin 20 fixedly secured to the flattened portions 13, the arrangement being such that the extensions 18 and the loop 19 define a lever or manipulator which likewise may be of an appropriate wire and which may be considered pivotedly or movably guided relative to the companion handle defined by the juxtapositioned extensions 14 and loop 15.

Fixedly interposed between the sides or posts 10 and 11 and at the upper portions thereof is the arcuate jaw or bar 21. This jaw may be fixedly anchored to the sides or tracks 10 and 11 in any well known manner and may be provided with a lip 22 for purposes of rigidity.

Vertically guided on the tracks or posts 10 and 11 is the slidably jaw generally designated 23 which characterizes a casing for removably holding a resilient pad 24 which may be of an appropriate rubber. This slidably jaw comprises complementary arcuate rear and front components 25 and 26, the latter characterizing a door and the former a support.

Component 25 is provided with two pairs of eye portions or coils defining vertically aligned ring shaped sockets. For example at one side of component 25 is the pair of vertically aligned sockets 27 and 28 and at the other side thereof is the pair of vertically aligned sockets 29 and 30. Component 25 which may be said to be a rearwardly disposed wall is of relatively thin sheet metal and the pairs of sockets 27 and 28, and 29 and 30 are integral with the body thereof as is the forwardly extending pad positioning flange 31 which with wall 25 characterize a support for the rubber pad as is well appreciated.

Arcuate component 26 is likewise of relatively thin sheet metal stock and is provided with a bearing or ring shaped socket 32 adapted to be removably interposed and fitting between the upper and lower guide sockets or bearings 27 and 28. For strengthening purposes component 26 is provided with an outwardly struck out rib or bead 33 and if desired flange 34 may be provided and this flange is integral with component 26 and extends rearwardly although interrupted by the

recess 35, and component 26 may be considered as a front wall of the slidably jaw.

Integral with and extending laterally of component 26 are the spaced and arcuate lips or keepers 37 having vertically aligned but spaced indented or grooved portions 38 for interlocking with aligned lips or detents 39 of the substantially T shaped and biased head 40 having reduced portion 41 bent out and integral with the ring shaped socket 42 interposed between and guided by ring shaped ears or sockets 29 and 30 slidably guided on post 11. Rotatably and slidably guided socket 42 together with its bent out T shaped head thus characterize a latch for disconectably interlocking with the resilient and flexible keepers or lugs 37.

Prior to mounting the pad supporting casing 23 on the guide posts or tracks 10 and 11 the reinforced link 43 is attached to ledge or flange 34 of the rear component or complement 25. This link is provided with spaced lugs such as 44 (one only being shown in Fig. 14 for purposes of illustration) positioned in and received by the spaced openings 45 after which the pointed terminals 46 thereof are upset, thus firmly anchoring the upper part of the offset link 43 to the rear complement or pad support 25 of the slidable jaw 23.

Thereafter socket or bearing 32 of the swingable complement or door 26 is interposed between the aligned sockets 27 and 28 of the rear complement 25 and the latch broadly denoted 47 characterized by the ring member 42 and head 40 is lined up with the aligned ring shaped sockets or ears 29 and 30 and interposed therebetween.

Subsequently aligned ring sockets or bearings 27, 32 and 28 are threaded on guide post or track 10 and ring sockets or ears 29, 42 and 30 are threaded on guide post or track 11. By this arrangement the companion components of the movable jaw are interlocked and bodily and slidably guided by the tracks 10 and 11.

But it should be appreciated that by such arrangement, component or door 26 is also swiveled, pivoted or hinged, thus permitting its displacement towards or away from the companion complementary portion or support 25 of the separable casing or jaw 23. It should also be observed that sockets 27 and 28 closely straddle the socket or bearing 32 of the swingable door to prevent wobbling thereof during its rotation while the interrupted flange or ledge 34 facilitates positioning of the door on closing whereby the spaced arcuate keepers 37 are set in alignment with and near the slidably guided sockets or ears 29 and 30 to permit the reduced portion 41 of the head 40 of the rotatable latch 47 to be received in gap 48 whereupon lips 39 coact to cam the spaced lips 37 towards ears 29 and 30 and ultimately snap into the aligned indents or grooves 38. In other words, latch 47 may be rotated manually to cam over and flex the resilient keepers 37 towards the rotatable sockets to be interlocked therewith, the spaced keepers 37 being normally slightly eccentrically arranged and slightly spaced from the sockets 29 and 30. By this arrangement lips 39 when interlocked with the keepers 37 are held in such relation due to the recoil or automatic retraction of keepers 37 after lips 39 snap into grooves 38.

Preparatory to closing of the swingable door, the rubber pad 24 is positioned on the forwardly extending flange or ledge 31 of the arcuate rear component or support 25, the rubber pad being provided with the spaced notches 49 to clear the upset ends 46 which sustain fixedly link 43 to

5

ledge 31. If desired spaced prongs 50 (Figs. 4 and 10) may be struck out of component 25 to facilitate the retention of the rubber pad after having been positioned onto ledge 31 and it should be noted that when the door 26 is closed the interrupted portion of rearwardly extending flange 34 defined by recess 35 is adapted to straddle and receive the upper portion of link 43 to permit the door to be disposed against the front face 51 (Fig. 11) of the positioning ledge 31 and slightly clamp the pad 24 against the upstanding wall of the rear complement 25.

Lengthwise of the link 43 is a struck out bead or rib 52 for reinforcing purposes, the link 43 having offset ends 53 and 54 with respect to the intermediate portion 55 thereof and the lower end 54 is provided with the spaced hooks 56 normally in alinement but which may be offset as indicated in Fig. 13 to be conveniently threaded into alined openings 57 (Fig. 1) of the juxtapositioned crank portions 17 and thereafter again alined.

With the rear component 25 of the slidable jaw slidably mounted on the guide posts or tracks 10 and 11 and where the front component or door is swingably and slidably mounted on post 10, and the upper end of link 53 is fixedly secured to the rear component 25, and where the latch is rotatably mounted on post 11 and guided between sockets 29 and 30 and the lower end 55 of link 43 has been pivotally connected to juxtapositioned extensions 17 of crank 16, the pivot pin 20 is driven through the flattened portions 13 and the juxtapositioned crank portions 17, thus providing a hinge connection, permitting the handle defined by loop 19, the extensions 18 and crank 16 to be manipulated to actuate link 43 to bodily displace the slidable jaw 23 on the guide posts 10 and 11.

Pursuant to mounting the slidable jaw on the frame, the fixed jaw or bar 21 may be fastened to the upper portion of the guide posts 10 and 11 by suitable rivets 58 and where the rubber pad is inserted in the slidable jaw, it may slightly project beyond the upper faces 59 thereof.

In Figs. 1 and 9, the slidable jaw 23 is fully retracted from the stationary bar or fixed jaw 21. In such relation eyelashes such as 60 (Fig. 10) may be positioned between the opened jaws 21 and 23. Thereafter loop 19 is manipulated towards loop 15, causing link 43 to slidably displace the movable jaw 23 to the position illustrated in Figs. 2 and 10. In such relation the jaws may be said to be closed. Further relative movement of the handles or manipulating portions causes the pad to give slightly, thus crimping the eyelashes as illustrated in Fig. 11 (only one being shown for purposes of illustration). Thereafter loop 19 is manipulated to retract the slidable jaw, permitting the crimped lashes to be withdrawn from the curler.

With the present invention, the pad 24 if worn out by use or decay may be quickly replaced and in this connection the operator merely manipulates head 40 of the rotatable latch 47 to remove lips or detents 39 from indents 38 of the resilient keepers 37, thus unlocking the swingable component or door of the slidable jaw. Subsequently the door may be fully opened, and full access is had to the rubber pad which may be easily removed and a new pad substituted after which the door is closed and locked upon manipulating the head of the rotatable latch to snap over the cam shaped keepers and interlock with the indents or notches 38 thereof.

In the closed relation of the rear and front components 25 and 26 these define a channeled

6

member in which the rubber pad is removably clamped.

The latch 47 in fact may be considered as coupling means for disengageably clamping the swingable door or pad retainer 26 against the pad support 25 and in effect removably interconnects the latter and the pad retainer while in their clamped relation against the pad to permit their shifting in unison towards or away from the upper fixed jaw.

Various changes may be made in details of construction and arrangement of parts without departing from the spirit of the invention or sacrificing any of the advantages therein.

15 I claim:

1. An eyelash curler comprising an arcuate fixed jaw, an arcuate shiftable jaw, means for movably guiding said shiftable jaw, means for displacing said shiftable jaw towards or away from said fixed jaw, the shiftable jaw comprising arcuate front and rear components, a pad interposed between said components, means for movably guiding said front component towards or away from said rear component to clamp said pad or to permit displacement of said pad away from said rear component, and means to removably sustain said front component against said pad when the latter is clamped by said front component.
2. An eyelash curler comprising an arcuate fixed jaw, an arcuate shiftable jaw, having spaced bearings, spaced means extending from and below said fixed jaw and cooperating with said bearings for movably guiding said shiftable jaw, means for displacing said shiftable jaw towards or away from said fixed jaw, the shiftable jaw comprising arcuate front and rear and separable components, a pad interposed between said components, means for movably guiding said front component towards or away from said rear component to clamp said pad or to permit displacement of said pad away from said rear component, and means for removably locking said front component when against said pad.
3. An eyelash curler comprising an arcuate fixed jaw, an arcuate shiftable jaw, means for movably guiding said shiftable jaw, means for displacing said shiftable jaw towards or away from said fixed jaw, the shiftable jaw comprising arcuate front and rear components defining a channeled member, a pad interposed between said components, means for movably guiding said front component towards or away from said rear component to close or open said member, and means for removably locking said front component.
4. In an eyelash curler, track means, a jaw having means slidably guided by said track means, said jaw comprising front and rear components defining a channeled member, a pad removably interposed between said components, means for movably guiding said front component towards or away from said rear component, means for removably locking said front component to hold the latter against said pad, a bar secured to said track means, and means carried by said curler for bodily driving said components towards or away from said bar.
5. In an eyelash curler, spaced tracks, a jaw having means slidably guided by said tracks, said jaw comprising front and rear complementary components defining a channeled member, a pad removably interposed between said components, means for rotatably guiding said front component towards or away from said rear com-

ponent, means for removably locking said front component to hold the latter against said pad, a bar fixed to said tracks, and means carried by said curler for bodily driving said components towards or away from said bar.

6. In an eyelash curler, a pair of spaced tracks, an arcuate jaw having spaced bearing means slidably guided by said tracks, said jaw comprising arcuate front and rear components defining a channeled member, a resilient pad removably interposed between said components, means mounted on one of said tracks for swingably guiding said front component towards or away from said rear component, means mounted on the other track of said pair for removably holding said front component against said pad, a bar secured to said tracks, and means for bodily driving said components towards or away from said bar.

7. In an eyelash curler, spaced tracks, a jaw having means slidably guided by said tracks, said jaw comprising front and rear complementary components defining a relatively elongated channeled member, spaced keeper means extending from said front component, a resilient pad removably interposed between said components, means slidably guided on one of said tracks or hingedly guiding said front component towards or away from said rear component, latch means for removably interlocking with said keeper means for holding said front component against said pad, means for rotatably and slidably guiding said latch means, a bar secured to said tracks, and means carried by said curler for bodily driving said components towards or away from said bar.

8. An eyelash curler comprising an arcuate fixed jaw, an arcuate shiftable jaw having bearing means, a pair of spaced track means for movably guiding said shiftable jaw, pivoted means for displacing said shiftable jaw towards or away from said fixed jaw, the shiftable jaw having an arcuate support, a pad removably mounted on said support, said shiftable jaw having a door for removably holding said pad on said support and having means rotatably and slidably guided on one of said track means of said pair and having keeper means, and locking means rotatably and slidably guided on the other track means of said pair for disengageably interlocking with said keeper means.

9. An eyelash curler comprising an arcuate fixed jaw, an arcuate shiftable jaw, means for movably guiding said shiftable jaw, the shiftable jaw having an arcuate support, a resilient pad removably mounted on said support, said shiftable jaw having a door for holding said pad on said support, means secured to said fixed jaw for movably guiding said door relative to said support, means for removably sustaining said door against said pad, and means for bodily displacing said door and support in a direction towards or away from said fixed jaw.

10. An eyelash curler comprising an arcuate fixed jaw, an arcuate shiftable jaw, means for movably guiding said shiftable jaw, the shiftable jaw having an arcuate support, a resilient pad mounted on said support, said shiftable jaw having a door for holding said pad on said support, means for rotatably guiding said door relative to said support, latch means for disconnectably locking said door, and means for bodily displacing said door and support in a direction towards or away from said fixed jaw.

11. In an eyelash curler, a casing having a rear wall having a forwardly extending flange, a resil-

ient pad removably seated on said flange and disposed against said wall, spaced sockets extending from said wall, said casing having a swingable door having a bearing interposed between said sockets, spaced ears extending from said wall, a pair of spaced posts for slidably guiding said sockets and ears, said bearing being mounted on one of said posts and rotatable and slidably thereon, a latch rotatably mounted on the other post of said pair, keeper means extending from said door for removably interlocking with said latch to disconnectably hold said door closed to sustain said pad against said wall, a bar secured to said posts, and means carried by said curler for bodily displacing said wall and door to displace said pad towards or away from said bar.

12. In an eyelash curler, a casing having a rear wall having a forwardly extending flange, a resilient pad removably seated on said flange and disposed against said wall, spaced sockets extending from said wall, said casing having a swingable door having a bearing interposed between said sockets, spaced ears extending from said wall, a pair of spaced posts for slidably guiding said sockets and ears, said bearing being mounted on one of said posts and rotatable and slidably thereon, a latch rotatably mounted on the other post of said pair and disposed between said ears and having detent means, keeper means extending from said door and having indent means for removably interlocking with said detent means to hold said door closed to removably sustain said pad against said wall, a bar secured to said posts, and means sustained by said curler and cooperating with said flange for bodily displacing said wall and door to shift said pad towards or away from said bar.

13. In an eyelash curler, a casing having an arcuate rear wall having a forwardly extending arcuate flange, a resilient pad removably seated on said flange and disposed against said wall, spaced sockets extending from said wall, said casing having a swingable arcuate door having a bearing interposed between said sockets, spaced ears extending from said wall, a pair of spaced posts for slidably guiding said sockets and ears, said bearing being mounted on one of said posts and rotatable and slidably thereon, a latch rotatably and slidably mounted on the other post of said pair and between said ears and having detent means and including a reduced portion, resilient cam shaped and spaced keeper means extending from said door for removably straddling said reduced portion and having indent means for removably interlocking with said detent means to hold said door closed to sustain said pad against said wall, a bar secured to said posts, and means carried by said curler for driving said flange for bodily displacing said wall and door to move said pad towards or away from said bar.

14. In an eyelash curler, a casing having a rear wall having a forwardly extending flange, a resilient pad removably seated on said flange and disposed against said wall, spaced and aligned sockets extending from said wall, said casing having a swingable door having a bearing interposed between said sockets, spaced and aligned ears extending from said wall, a pair of spaced posts for slidably guiding said sockets and ears, said bearing being mounted on one of said posts and rotatable and slidably thereon; a latch rotatably mounted on the other post of said pair and guided between said ears, keeper means extend-

ing from said door for removably interlocking with said latch to hold said door closed to sustain said pad against said wall, a bar secured to said posts, a link connected to said flange, and pivoted means for driving said link to displace said casing towards or away from said bar.

15. In an eyelash curler, a casing having a rear wall having a forwardly extending flange, a resilient pad removably seated on said flange and disposed against said wall, spaced and alined sockets extending from said wall, said casing having a swingable door having a bearing rotatably interposed between said sockets, spaced and alined ears extending from said wall, a pair of spaced posts for slidably guiding said sockets and ears, said bearing being mounted on one of said posts and slidable thereon; a latch rotatably mounted on the other post of said pair and slidably guided between said ears and along said last mentioned post, keeper means extending from said door for removably interlocking with said latch to hold said door closed to sustain said pad against said wall, a bar secured to said posts, and actuator means carried by said curler for shifting said casing to displace said pad towards or away from said bar, said door having a rearwardly extending flange cooperating with said first mentioned flange to position said keeper means adjacent said ears on movement of said door to its closed position, said actuator means comprising a link secured to said forwardly extending flange and said rearwardly extending flange including means for removably receiving said link.

16. In an eyelash curler, a resilient pad, a support for said pad, a door movable towards or away from said support for removably holding said pad on said support, means movably connecting said door to said support, a frame having a fixed bar and having means for slidably guiding said support and door on said frame, and means for bodily displacing said support and door towards or away from said bar.

17. In an eyelash curler, a resilient pad, a support for said pad, a door swingable towards or away from said support for removably holding said pad on said support, a frame having a fixed bar and having means for slidably guiding said support on said frame and hingedly and slidably guiding said door, means for removably locking said door, and means for bodily displacing said support and door towards or away from said bar.

18. In an eyelash curler, a resilient pad, a support for said pad, a door rotatable towards or away from said support for removably holding said pad on said support and having keeper means, a frame having a fixed bar and having spaced means for slidably guiding said support on said frame and one of said spaced means rotatably and slidably guiding said door, latch means for removably locking said door, and means for bodily displacing said support and door towards or away from said bar.

19. In an eyelash curler, a frame having a pair of spaced posts, a fixed jaw bridging said posts and secured thereto, a shiftable jaw comprising a support and a door, a pad removably sustained by said support and projecting slightly thereabove, spaced sockets extending from said support and slidably guided on one post of said pair, a bearing extending from said door and rotatably and slidably guided on said last mentioned post between said sockets whereby said door may be swung towards said pad to clamp the latter against said support or away from said support whereby said pad may be removed therefrom, spaced keeper

means on said door and defining a gap, spaced ears extending from said support and slidably guided on the other post of said pair, a latch interposed between said ears and rotatably and slidably guided on said last mentioned post and including a head and having a reduced portion, said reduced portion adapted to be removably received in said gap on rotation of said latch for removably interlocking said head with said keeper means whereby said door is held closed to sustain said pad against said support, and actuator means connected to said frame and shiftable jaw whereby said support, door, sockets, bearing, ears, keeper means and latch may be bodily and slidably displaced towards or away from said fixed jaw.

20. In an eyelash curler, a frame having a pair of spaced posts, a fixed jaw bridging said posts and secured thereto, a shiftable jaw comprising a support having a forwardly extending flange and a door having a rearwardly extending flange, a pad removably sustained on said forwardly extending flange and projecting slightly above said support, spaced sockets extending from said support and slidably guided on one post of said pair, a bearing extending from said door and rotatably and slidably guided on said last mentioned post between said sockets whereby said door may be swung towards said pad to clamp the latter against said support or away from said support whereby said pad may be removed therefrom, spaced keeper means on said door and defining a gap, spaced ears extending from said support and slidably guided on the other post of said pair, said rearwardly extending flange cooperating with said forwardly extending flange for positioning said spaced keeper means adjacent said ears on rotatably displacing said door towards said support, a latch interposed between said ears and rotatably and slidably guided on said last mentioned post and including a head and having a reduced portion, said reduced portion adapted to be removably received in said gap on rotation of said latch for removably interlocking said head with said keeper means whereby said door is held closed to sustain said pad against said support, and actuator means connected to said frame and said forwardly extending flange whereby said support, door, sockets, bearing, ears, keeper means and latch may be bodily and slidably displaced along said posts towards or away from said fixed jaw.

21. The eyelash curler according to claim 20 wherein said rearwardly extending flange has a cutaway portion for receiving a portion of said actuator means to permit complete closing of said door and the positioning of said keeper means adjacent said ears.

22. The eyelash curler according to claim 20 wherein said head embodies detent means and said spaced keeper means is resilient and includes indent means adapted to removably receive said detent means in the full closed relation of said door upon rotation of said latch towards said door.

23. In an eyelash curler, a frame having a pair of spaced posts, a fixed jaw bridging said posts and secured thereto, a shiftable jaw comprising a support and a door, a pad removably sustained by said support and projecting slightly thereabove, socket means extending from said support and slidably guided on one post of said pair, a bearing extending from said door and rotatably and slidably guided on said last mentioned post adjacent said socket means whereby said door may be

11

rotatably swung towards said pad to clamp the latter against said support or away from said support whereby said pad may be removed therefrom, keeper means on said door, socket means extending from said support and slidably guided on the other post of said pair, a latch adjacent said last mentioned socket means and having means rotatably and slidably guided on said last mentioned post and having means for removably interlocking with said keeper means whereby said door is held closed to sustain said pad against said support, and means connected to said frame and shiftable jaw whereby said support, door, socket means, latch and keeper means may be bodily and slidably displaced towards or away from said fixed jaw.

24. In an eyelash curler, a frame having a pair of spaced posts, a fixed jaw bridging said posts and secured thereto, a shiftable jaw comprising a support and a door, a pad removably sustained by said support and projecting slightly thereabove, socket means integral with and extending from said support and slidably guided on one post of said pair, a bearing integral with and extending from said door and rotatably and slidably guided on said last mentioned post adjacent said socket means whereby said door may be rotatably swung towards said pad to clamp the latter against said support or away from said support whereby said pad may be removed therefrom, keeper means on said door and spaced from said bearing, socket means integral with and extending from said support and slidably guided on the other post of said pair, a latch carried by said shiftable jaw and movably guided adjacent said last mentioned socket means and having means for removably interlocking with said keeper means to removably sustain said door against said pad, and means connected to said frame and said support whereby the latter, said door, socket means, latch, and keeper means may be slidably and bodily displaced towards or away from said fixed jaw.

25. In an eyelash curler, spaced track means, a bar fixed to said track means, a movable jaw having means slidably guided by said track means, said jaw comprising a pair of front and rear components, a pad interposed between said components, actuating means carried by said curler for displacing said movable jaw towards or away from said bar, means for movably guiding one of said components relative to the other component of said pair for opening and closing of said movable jaw, one of said components defining pad supporting means and the other component of said pair defining pad retaining means, and means for disengageably coupling said pad supporting means and pad retaining means for removably clamping said pad and for effecting displacement of said pad supporting means and said pad retaining means in unison while in their

12

clamped relation against said pad upon manipulation of said actuating means.

26. In an eyelash curler, spaced track means, a bar fixed to said track means, a movable jaw having means slidably guided by said track means, said jaw comprising a pair of front and rear components, a pad interposed between said components, actuating means carried by said curler for displacing said movable jaw towards or away from said bar, a hinged connection for rotatably guiding one of said components relative to the other component of said pair for opening and closing of said movable jaw, one of said components defining sustaining means for supporting said pad and the other component of said pair defining swingable means for retaining said pad, and means for coupling said sustaining means and swingable means for removably clamping said pad and for effecting displacement of said sustaining means and said swingable means in unison while in their clamped relation against said pad upon manipulation of said actuating means.

27. In an eyelash curler, a frame having spaced posts, an arcuate bar fixed to said posts, a resilient pad, a movable jaw having means slidably guided by said posts and comprising a pair of arcuate complementary members for removably clamping said pad, a hinged connection for one of said members whereby said last mentioned member may be swung towards or away from the other member of said pair to close or open said members respectively, coupling means for disconectably holding said members closed to clamp said pad whereby said members may be bodily shifted in unison towards or away from said bar, and means carried by said frame for actuating said movable jaw for bodily shifting said members towards or away from said bar.

28. In an eyelash curler, spaced track means, a bar fixed to said track means, a movable jaw having means slidably guided by said track means, said jaw comprising a pair of front and rear components, a pad interposed between said components, actuating means carried by said curler for displacing said movable jaw towards or away from said bar, a hinged connection for rotatably guiding one of said components relative to the other component of said pair for opening and closing of said movable jaw, one of said components defining pad supporting means and the other component of said pair defining pad retaining means, and coupling means for disengageably connecting said pad supporting means and pad retaining means for removably clamping said pad and for effecting displacement in unison of said pad supporting means and said pad retaining means while in their clamped relation against said pad upon the manipulation of said actuating means.

CHARLES M. PALMER.
